UNITED STATES PATENT OFFICE

THOMAS N. DELIGIANES, OF CHICAGO, ILLINOIS

DESIGN FOR A COUNTER FIXTURE

Application filed October 2, 1929. Serial No. 32,916. Term of patent 14 years.

To all whom it may concern:

Be it known that I, THOMAS N. DELIGIANES, a citizen of the United States, residing at Chicago, in the county of Cook and State of Illinois, have invented a new, original, and ornamental Design for a Counter Fixture, of which the following is a specification, reference being had to the accompanying drawing, forming a part thereof.

The figure is a perspective view of the counter fixture embodying my design.

I claim:

The ornamental design for a counter fixture substantially as shown.

THOMAS N. DELIGIANES.
